UNITED STATES PATENT OFFICE.

LEWIS R. FERGUSON, OF PHILADELPHIA, PENNSYLVANIA, AND RUDOLPH J. WIG, OF WASHINGTON, DISTRICT OF COLUMBIA.

MEANS FOR CONTROLLING THE OPERATION OF CONCRETE-MIXING MACHINES, &c.

1,282,558.

Specification of Letters Patent. Patented Oct. 22, 1918.

Application filed March 15, 1918. Serial No. 84,349.

To all whom it may concern:

Be it known that we, LEWIS R. FERGUSON, a citizen of the United States, residing at Philadelphia, in the county of Philadelphia and State of Pennsylvania, and RUDOLPH J. Wig, residing at Washington, in the District of Columbia, have invented certain new and useful Improvements in Means for Controlling the Operation of Concrete-Mixing Machines, &c.; and we hereby declare that the following is a full, clear, and exact description thereof, reference being had to the accompanying drawings, which form part of this specification.

This invention relates to machines for mixing materials, and the object of the invention is to insure that after the materials have been introduced into the mixer they shall be stirred or agitated therein for a sufficient length of time, or number of operations of the mixer, to insure the proper mixing and commingling thereof before they can be discharged.

The invention is particularly designed for use with concrete mixers; and we will explain the invention as applied to such a machine as this will enable others to readily understand the invention and adapt it to machines for mixing other materials within the scope of the invention.

In the ordinary method of manufacturing concrete the materials, such as cement, water, and coarse aggregates, such as sand, gravel, broken stone, etc., are placed in a revolving drum, and commingled or mixed by rotating the drum in the well known manner. It is important to insure good uniform concrete that the materials shall be thoroughly mixed and also that different batches of material shall be of the same relative proportions and equally well mixed. Heretofore the mixing has been left to the judgment of a workman, and the drum being permitted to rotate a greater or less number of times, at the caprice of the operator, the different batches of materials are not equally mixed; and some batches are not properly mixed.

When applied to machines for mixing concrete the present invention will automatically insure that the materials shall all be thoroughly mixed, and that successive charges of materials shall be equally mixed; and this we accomplish by providing novel means whereby after the materials are intro-

duced into the mixer the latter must make a predetermined number of operations before the material can be discharged therefrom.

When applied to a rotary drum mixer the invention would insure the rotation of the drum for a certain predetermined number of times after a charge is admitted thereto before such charge can be removed therefrom.

The accompanying drawings conventionally illustrate one embodiment of the invention applied to a well known type of concrete mixing machine, but we do not consider the invention restricted to the particular construction of parts of the device illustrated in the drawings, and those skilled in the art will readily understand how the invention can be adapted for use with various other kinds of mixers, all within the scope of the appended claims summarizing the invention.

In said drawings:

Figure 1 conventionally illustrates a side elevation of part of a rotary drum type of machine for mixing concrete, with one embodiment of our invention applied thereto for automatically controlling the operation thereof.

Fig. 2 is an enlarged detail view of the controlling devices.

Fig. 3 is a plan view of the controlling devices shown in Fig. 2 with the clutch engaged.

Fig. 4 is a further enlarged detail plan view showing the clutch disengaged.

Fig. 5 is a detail section on the line 5-5, Fig. 4; and

Fig. 6 is a detail of the clutch operating dog.

In said drawings the cylindrical drum or mixing chamber A is mounted upon rollers B on a framework C, and is adapted to be rotated by suitable means, not shown, in the usual manner. A charging hopper D is attached to a shaft d by which it is hinged to one side of the frame, and is adapted when raised to discharge materials loaded therein into the drum A. A discharge chute E is hinged on a shaft F supported on the frame at the end of the drum opposite the charging hopper. Said discharge chute is held in the inoperative position shown in full lines Fig. 1 when the drum is rotated to mix the materials therein, and may be turned to the discharging position indicated

105

110

in Fig. 2, when it is desired to discharge mixed materials from the drum. The aforesaid parts are of a well known type and therefore need no further explanation herein, and are simply conventionally illustrated for the purpose of imparting a ready understanding of our invention when applied to such a mixer.

Beside the drum A is a longitudinally movable bar 1 mounted in standards 1^a attached to bars 1^b attached to the frame C. Mounted on the bars 1^b adjacent the charging hopper is a cam-member 2 which has an arm 2^a connected by a link 2^b with a crank 2^c attached to the shaft d to which the charging hopper D is secured. The cam portion of cam 2 is adapted to engage with the adjacent end of the bar 1 and force the latter to move longitudinally when the charging hopper D is raised.

The bar 1 may be provided with a roller 1^e for engagement with the cam 2 to reduce friction. Adjacent the other end of the bar 1 is a cam 3 pivotally mounted on a support 3^a and having an arm 3^b connected by a link 3^c to a crank arm 3^d on the shaft F upon which the discharge chute E is mounted. The cam portion of this cam 3 is adapted to engage the adjacent end of the bar 1, which may be provided with a roller 1^e to lessen friction.

The parts are so constructed and arranged that if the charging hopper is raised to discharge a load of material into the mixer A, it will in the act of raising, rock the shaft d and through crank 2^c and link 2^b cause cam 2 to move bar 1 to the right, and said bar will engage the cam lever 3 and return or hold the discharge chute E in inoperative position, as shown in full lines in Fig. 1; and bar 1 will lock cam 3 in this position so as to hold the discharge chute inoperative until the bar 1 is retracted. When the charging hopper D is lowered the cam 2 is returned to normal position, but leaves cam 3 locked by bar 1 with the discharge chute in inoperative position. But means are provided for thereafter automatically retracting the bar 1 so as to release cam 3 and free the discharge chute.

As shown in the drawings the bar 1 is retracted by novel means after a certain number of operations or revolutions of the mixer A as follows: Bar 1 is provided with a rack portion 1^e which meshes with a pinion 4^a on a shaft 4 journaled in bearings on standards 5 attached to the bars 1^b. The pinion 4^a is loose on shaft 4 but has a clutch face which is adapted to be engaged by a clutch member 6^e splined on shaft 4 and adapted to be normally held in engagement with the pinion by suitable means, a spring 5^a being indicated.

On shaft 4 is keyed a worm gear 4^c which meshes with a worm 6 on a shaft 6^a journaled in bearings in the standard 5; and on

the outer end of this shaft 6^a is a tappet wheel 6^b which is adapted to be engaged by one or more members 6^e (which may be pins, studs or rollers) attached to the outer side of the drum A as shown. Preferably wheel 6^b has a plurality of teeth or fingers which may be successively engaged by the member 6^e on the drum; so that during the rotation of the mixer the wheel 6^b, will be engaged and turned and thus through the worm impart rotation to the shaft 4; and if the clutch 6^e is engaged with pinion 4^a said pinion will be turned in a direction to cause it to retract bar 1 and disengage it from the cam 3.

As shown the clutch may be disengaged from pinion 4^a by means of a yoke 7 on one end of a bell crank lever pivoted at 7^a on a suitable support; and the outer arm 7^b of this lever is adapted to be engaged by a dog 8^a pivoted on a sliding rod 8^b which is supported in brackets 1^a, 1^f parallel with and beside bar 1; and this rod 8^b is connected by a link 8^c with the cam 2, in such manner that when the charging hopper D is raised the rod 8^b is moved so as to cause dog 8^a to engage arm 7^b and disengage the clutch before the cam 2 engages and moves bar 1.

The clutch 6^e should be disengaged from the clutch pinion 4^a before the cam 2 moves bar 1 to the right and should hold the clutch disengaged until the bar 1 has been fully moved to the right. For this purpose arm 7^b is shown as provided with an extension or finger 7^c which is so proportioned that after dog 8^a engages arm 7^b and causes it to disengage the clutch said dog moves against the finger 7^c and holds the clutch disengaged while rod 8^b and bar 1 move to the right and until the roller 1^e has engaged the dwell portion 3^e of cam 3; then the trip 8^a clears finger 7^c and the clutch can reengage pinion 4^a.

When the hopper D is lowered the cam 2 is returned to normal position while the bar 1 remains in its projected position locking cam 3; but rod 8^b is returned by the movement of the cam 2 and in returning the dog 8^a rides idly over the finger 7^c and arm 7^b of the clutch lever until it clears same. The dog 8^a is normally held in position to positively actuate the arm 7^b when the rod 8^b moves to the right by means of a pin 8^e on rod 8^b but when the rod 8^b moves to the left the trip 8^a can yield and ride over the finger and lever 7^c as described; but will be returned to normal position when it clears the lever by means of a spring 8^f.

When the charging hopper D is elevated to discharge material into the mixer A the cam 2 is turned, first causing link 8^c to move rod 8^b to the right. The dog 8^a on rod 8^b engages the arm 7^b of the clutch shifting lever and disengages clutch 6^e

from pinion 4^a permitting said pinion to revolve freely upon the shaft 4. The length of the finger 7^c is such that the dog 8^a continues to hold the clutch 6 out of mesh until 5 the bar 1 enters the dwell 3^c in the cam 3; then the dog 8^a clears the finger 7^c and the spring 5^a causes the clutch 6^c to again engage pinion 4^a. As cam 2 revolves clockwise it first causes the link 8^c to move, and 10 after the clutch 6^c is disengaged it causes bar 1 to move to the right. As bar 1 moves to the right, the pinion 4^a is free to turn on shaft 4, and bar 1 operates cam 3; the cam 3 moves the discharge chute E to 15 operative position.

As the mixer drum rotates, the member 6^e successively engages the teeth of the tally wheel 6^b and revolves the worm, which in turn revolves the shaft 4 and clutch 6^c and 20 the latter operates pinion 4^a which engages the rack 1^e and moves the bar 1 to the left. The rack 1^e is of such length that after bar 1 has moved far enough to the left to permit the discharge chute to move to discharging 25 position, the spur gear will enter a slot or notch 1^m in the bar 1 and can then freely revolve without further moving the bar.

When the charging hopper D is lowered, after discharging into the mixer the cam 2 30 revolves counterclockwise and the rod 8^b is moved to the left but the dog 8^a attached to rod 8^b does not operatively engage the clutch shifting arm but rides over it, permitting the clutch 6^c to remain engaged 35 with pinion 4^a until the rod 8^b is again moved forward by the lifting of the charging hopper D.

It will be seen from the foregoing that when the mixer is charged it cannot be 40 emptied until after it has made a predetermined number of revolutions, and this is preferably accomplished, in the form of mixer shown, by locking the discharge chute in inoperative position. The particular construction of the devices for thus automatically controlling the operation of the mixer, can obviously be varied and would be varied to suit the particular type or character of mixer to which the invention is applied.

50 While we have described the invention as applied to a concrete mixing machine having a charging hopper as D it is obvious that the cam 2 might be operatively connected with any member which has to be turned to admit material into a mixer, and the invention is not limited to use in connection with a charging hopper as any device which has to be shifted to admit material into the mixer might be operatively 55 connected with this cam so that when material is admitted cam 2 will be shifted, and the cam 3 might be connected with any suitable discharging device or means for controlling the discharging or emptying of 60 the mixer so that when any material is ad-

mitted into the mixer the discharge will be automatically prevented until the mixer has performed a certain number of operations sufficient to mix the material therein.

The essential novel characteristic of our 70 invention is that when the mixing machine has been charged it must go through a certain number of operations before the material can be discharged and the particular means for charging, or the particular construction of the mixer, or the particular discharging means, or the manner in which the mixer is emptied after the mixing is completed, are not features of the present invention; nor is the particular means by 75 which such desired operation of the mixer is accomplished a feature of the present invention, for those skilled in the art will appreciate the utility of the invention and be able to adapt it in various forms and constructions within the scope of the invention to various different types of mixers. The invention is also applicable to machines for mixing other kinds of materials as above stated although it is primarily designed for 80 use with concrete mixing machines.

The parts should be so proportioned or adjusted that after the mixer is charged it has to automatically make a predetermined number of operations or rotations before 95 material can be discharged; this, in the embodiment illustrated in the drawings, would depend upon the relative proportion of the gearing, the length of travel of the bar, the size and number of teeth on the wheel; and 100 the number of engaging members on the drum.

What we claim is:

1. In combination, a mixing machine comprising a mixer, discharging and charging 105 devices therefor, and means controlled by the charging device and operable by the mixer to govern the operation of the discharging device.

2. In combination, a mixer, a charger; and 110 controlling means adapted to be set into operative condition by the charger and then operated by the mixer; whereby the mixer when charged must make a number of operations before it can be emptied.

3. In a mixing machine the combination 115 of a mixer; means for admitting material therein; means for discharging the material; and means for locking the discharger; with a charger; and controlling means adapted to be set by the charger and then operated by the mixer; whereby after the material is admitted into the mixer the discharging means is kept locked until the mixer has performed a predetermined number of operations.

4. In a mixing machine the combination 120 of a mixer; charging means; and discharging means; with means set by the charging means whereby when the charging means admits material into the mixer the discharg-

ing means is held in inoperative position; and means operated by the mixer whereby the discharging means is released after the mixer has performed a predetermined number of operations.

5. In a mixing machine the combination of a mixer; a charger; a discharger; locking means for the discharger adapted to be set by the charger when the latter is raised; and 10 controlling means for the locking means operated by the mixer; whereby when the charger is moved to charge the mixer the discharger is locked until the mixer has made a given number of revolutions.

15. 6. In a mixing machine the combination of a rotary drum; means for charging the drum; controlling means set by the charger; and means operated by rotation of the drum and engaging said controlling means where-

20 by when the drum is charged it must make a predetermined number of rotations before the material can be discharged therefrom.

7. In a concrete mixing machine; the combination of a rotary drum; a charging device; discharging means; controlling means set by the charger and means operated by rotation of the drum and engaging said controlling means whereby when the charger is operated to admit material into the drum the 30 discharging means is automatically locked until the drum has made a predetermined number of rotations.

8. In a concrete mixing machine, the combination of a rotary drum; a charging device; and a discharger; with means set by the charger whereby when the charger is moved to charge material into the drum the discharger is automatically locked in inoperative position; and means actuated by the 40 drum whereby the discharger is unlocked when the drum has made a predetermined number of rotations.

9. In a concrete mixing machine; the combination of a mixer; a movable member for 45 charging the mixer; and a discharging means; with locking means; means actuated by the movement of the charging member whereby when the charging member is moved to admit material into the mixer the locking means is caused to lock the discharging means in inoperative position; and means operated by the mixer whereby after the return of the charging member to normal position the mixer must make a given 55 number of rotations before the discharging means is released.

10. In a concrete mixing machine; the combination of a mixer; a movable hopper for charging the mixer; and a movable dis- 60 charger; with locking means set by the raising of the charging hopper, whereby when the hopper is elevated the discharger is locked in inoperative position; and means operated by the drum and engaging said locking 65 means whereby the mixer must make a pre-

determined number of rotations before the discharger can be released.

11. In a concrete mixing machine the combination of a mixer, a charger, a discharger, and means for holding the discharger inoperative; with means operatively connected with the charger and adapted to cause said holding means to lock the discharger in inoperative position; and means operated by the mixer for automatically releasing the 75 said discharger after the mixer has made a predetermined number of rotations.

12. In a concrete mixing machine the combination of a mixer, a charger, a discharger, a cam connected with the discharger for 80 locking it in inoperative position, a slideable bar adapted to engage said cam; and a second cam operatively connected with the charger and adapted to engage said bar when the charger is raised and cause said 85 bar to engage the discharger controlling cam and hold the discharger in inoperative position.

13. In a concrete mixing machine the combination of a rotary drum, a movable hopper 90 for charging the drum, and discharging means set by the hopper; with means whereby when the hopper is moved to charging position the discharging means is automatically locked in inoperative position, and 95 means operated by the drum whereby after the hopper is returned to normal position the drum must make a predetermined number of rotations before the discharging means is released.

14. In a concrete mixing machine the combination of a rotary drum, a movable hinged hopper for charging the drum, and a movable discharger chute; with means set by the hopper whereby when the hopper is ele- 105 vated the chute is locked in inoperative position, and means operated by the drum whereby after the lowering of the hopper the drum must make a predetermined number of rotations before the discharger is released. 110

15. In a concrete mixing machine the combination of a rotary drum, a charging hopper at one end thereof, a discharge chute at the opposite end thereof, a cam connected with the discharge chute for locking it in 115 inoperative position, a slideable bar adapted to engage said cam, and a second cam operatively connected with the charging hopper and adapted to engage said bar when the hopper is raised and cause said bar to 120 engage and move the discharge controlling cam and hold the discharge chute in inoperative position.

16. In a concrete mixing machine the combination of a mixer, a charger, a discharger, 125 a cam connected with the discharger for locking it in inoperative position, a slideable bar adapted to engage said cam; and a second cam operatively connected with the charger and adapted when the charger is raised to 130

- project said bar to engage the discharger controlling cam and hold the discharger in inoperative position; with means for reTRACTING the bar, a clutch for disengaging 5 said operating means, and means whereby the said clutch is disengaged while the charger cam is actuating the bar, the clutch being reengaged when the charger cam frees the bar, substantially as described.
- 10 17. In a concrete mixing machine the combination of a rotary drum, a charging hopper at one end thereof, a discharge chute at the opposite end thereof, a cam connected with the discharge chute for locking it in inoperative position, a slideable bar adapted 15 to engage said cam, and a second cam operatively connected with the charging hopper
- and adapted when the hopper is raised to project said bar to engage the discharge controlling cam and hold the discharge chute 20 in inoperative position; with a gearing adapted to be operated by the said drum, means operated by said gearing for retracting the bar, a clutch for disengaging said operating means, and means whereby the 25 said clutch is disengaged when the charging cam is actuating the bar and reengaged when the charging cam frees the bar, substantially as described.

In testimony that we claim the foregoing 30 as our own, we affix our signatures.

LEWIS R. FERGUSON.
RUDOLPH J. WIG.
